UNITED STATES PATENT OFFICE

LOUIS V. ARONSON, OF NEWARK, NEW JERSEY, ASSIGNOR TO ART METAL WORKS, INC.,
A CORPORATION OF NEW JERSEY

SPARKING TOY

Application filed May 3, 1928. Serial No. 274,688.

My invention relates to sparking toys and the main object of the invention is to provide a simple and efficient toy which upon being whirled first in one direction and then in the other direction, will produce a series of sparks. Further and more specific objects, features and advantages will more clearly appear from the detail description given below taken in connection with the accompanying drawings which form a part of this specification.

In the drawings, Fig. 1 is a perspective of a device embodying the invention in one form. Fig. 2 is a transverse section of the whirling members thereof, Fig. 3 illustrates in perspective the various parts thereof disassembled, Fig. 4 is a view similar to Fig. 1 illustrating a modification, Fig. 5 is a transverse section of the whirling members of the device shown in Fig. 4, and Fig. 6 is a perspective of the various parts thereof disassembled.

Referring to Figs. 1, 2 and 3,—7 and 8 represent two sheet metal discs, each provided with openings or windows 9 and centrally disposed holes 10 and 11 respectively. Arranged flat against the inside faces of the discs 7 and 8 and so as to cover the window openings 9 and form colored panes therefor, are colored celluloid sheets 12 and 13 respectively, these sheets being provided with centrally disposed holes 14 and 15 respectively. Arranged flat against the inside faces of the sheets 12 and 13 are discs 16 and 19 respectively having abradant surfaces on their inside faces. These sheets may be formed of heavy emery paper and like the sheets 12 and 13, may be shaped in the form of discs. They are also provided with central holes 18 and 17 respectively. 20 represents a spacer comprising a tubular member internally screw-threaded at each end thereof. 21 and 22 represent U shaped members each provided with perforated outwardly extending ears 23. The base portions of these U shaped members are provided with holes adapted to receive the screws 24 and 25 respectively.

The discs 16, 12, 7 and the member 21 are all rigidly secured to one end of the spacer 20 in the order named by the screw 24 which

passes through the holes 10, 14 and 18 and engages with the screw threads in one end of the spacer. The discs 19, 13, 8 and the member 22 are all secured to the other end of the spacer 20 in the order named by the screw 25 which passes through the holes 11, 15 and 17 and engages with the screw threads in said other end of the spacer 20. The parts so far described are thus all rigidly connected together and form a unitary whirling member. 60

The discs 7 and 8 are provided with stamped out inwardly facing grooves 28 and 29 respectively at their peripheries which aid in giving rigidity to the discs. Journalled on the spacer 20 and freely rotatable about the same, is a weighty disc member 26 preferably composed of a relatively thick piece of iron or steel and provided with a plurality of spaced holes therethrough, through which are inserted and rigidly secured sticks of pyrophoric alloy material 27, which project from both sides of the disc 26 and are adapted to engage the abradant surfaces 16 and 19 respectively when the device is whirled.

Passing through the apertures in the ears of the U shaped member 21 are the ends of two lengths of string 30 and 31 respectively. The ends are knotted to prevent them from slipping out of the apertures. The outer ends of these strings are integrally or otherwise connected to form a loop which passes through a hole in a wooden ball 32. Passing through the apertures in the ears of the U shaped member 22 are the ends of two lengths of string 33 and 34 respectively, the ends of which are also knotted to prevent them from slipping out of the apertures. The outer ends of these strings are also integrally or otherwise connected to form a loop which passes through a hole in a wooden ball 35.

In operation the operator firmly grasps the balls 32 and 35, one in each hand, and by alternately pulling the same apart to put the strings under tension and then relieving the tension, the strings are caused to be twisted first in one direction and then in the other direction in a manner well understood by those skilled in the art. This causes the whirling member comprising the discs 7 and

8 and parts rigidly connected thereto, to be rotated first rapidly in one direction and then quickly reversed and rotated rapidly in the other direction and so on, alternately, with the change from one to the other taking place suddenly. The member 26, however, because of its weight and the momentum due thereto, lags behind the other parts in the rotation thereof, so that the discs 7 and 8 and 10 the abradant material 16 and 17 respectively carried thereby, are caused to rotate with respect to the pyrophoric pieces 27 engaging the same, whereby the pyrophoric pieces 27 are abraded causing showers of sparks to be 15 issued therefrom which are visible through the window openings 9 as well as through the peripheral opening between the discs 7 and 8. Through this opening the sparks will appear to be white or of natural color and the sparks 20 may be projected radially beyond the edges of the discs 7 and 8. The disc 12 may be colored red and the disc 13 may be colored green, whereby the sparks when viewed through the thus colored window panes on one side will 25 appear to be red and when viewed through the thus colored window panes on the other side, will appear to be green.

Referring to Figs. 4, 5, and 6, the parts 7, 8, 12, 13, 16, 19, 20, 26 and 27 are the same as 30 Figs. 1, 2 and 3 except that the discs 12 and 13 are each variegated in color. For example, they are provided with central bands colored red and outside bands 37 colored blue, so that when viewed from either side the sparks will 35 appear alternately as of red and blue color. Instead of using the screws 24 and 25 and U shaped members 21 and 22, in this form, I have substituted therefor screws 38 and 39 provided with heads 40 and 41 respectively 40 through which extend apertures 42 and 43 respectively. A string 44 is tied together at its ends forming an endless string passing through the aperture 42 and through the wooden ball 32 so that there are in effect two 45 strings extending from this side of the whirling member. Another string 45 is also tied together at its ends to form another endless string which passes through the aperture 43 and through the ball 35, so that there are in 50 effect two strings extending from the other side of the whirling member, and the device may be operated thereby in the same manner as described in connection with Figs. 1, 2 and 3.

Also in Figs 4, 5 and 6, I have shown a sheet metal band 46 extending around the periphery of the device so as to substantially enclose the disk 26 and other parts between the discs 7 and 8. The band 46 is held in place by having its edges seated in the grooves 28 and 29. The band 46 is provided with window openings 47 and laid on the inside of the band 46 is a band of colored celluloid 48 to provide colored transparent panes for the window 55 openings 47 through which the sparks may

be viewed when looking at the device radially. The band 48 may be variegated in color so that the sparks appearing through the window openings 47 will appear to be of various colors.

While I have described my improvements in detail and with respect to certain preferred forms thereof, I do not desire to be limited to such details or forms since many changes and modifications may be made and the invention 70 embodied in widely different forms and kinds of devices without departing from the spirit and scope of the invention in its broader aspects. Hence I desire to cover all forms and embodiments coming within the language or scope of any one or more of the appended claims.

What I claim as new and desire to secure by Letters Patent, is:

1. A toy having a whirling member, two 85 strings extending from one side thereof and connected together at their outer ends, two strings extending from the other side thereof and connected together at their outer ends, said strings serving as means by which the member may be whirled, about an axis passing therethrough, said member including a disc with colored window panes therein, a weighty member rotatable with respect to the first member about the same axis whereby when the first member is rotated it is rotated with respect to the weighty member, an abradant surface on one of said members and a pyrophoric piece carried by the other member and engaging said abradant surface to 90 produce sparks when the first member is whirled, which sparks are visible through 95 said colored panes.

2. A toy having a whirling member, two 100 strings extending from one side thereof and connected together at their outer ends, two strings extending from the other side thereof and connected together at their outer ends, said strings serving as means by which the member may be whirled, about an axis passing therethrough, said member comprising two spaced discs rigidly connected together 105 at said axis, a weighty member journaled about said axis between said discs whereby when the first member is whirled it is rotated 110 with respect to the weighty member, abradant material carried by one of said members and pyrophoric means carried by the other member and engaging said abradant material 115 when the first member is whirled.

3. A toy having a whirling member, two 120 strings extending from one side thereof and connected together at their outer ends, two strings extending from the other side thereof and connected together at their outer ends, said strings serving as means by which the member may be whirled about an axis passing therethrough, said member comprising two spaced discs rigidly connected together 125 at said axis, a weighty member journaled 130

- about said axis between said discs whereby when the first member is whirled it is rotated with respect to the weighty member, abradant surfaces carried by said discs respectively, 5 pyrophoric pieces carried by said weighty member and engaging said abradant surfaces respectively when the first member is whirled.
4. A toy having a whirling member, means for whirling the same first in one direction and then in the other direction, said whirling member comprising two spaced discs rigidly connected, and provided with colored windows, a weighty member journaled between said discs and free to rotate with respect thereto, abradant material carried by one of said members, pyrophoric means carried by the other of said members and engaging said abradant material to produce sparks visible through said windows when the first 15 member is whirled.
5. The combination of two spaced discs, with window openings therein, sheets of colored material covering said openings, two sheets of abradant material, one on the inside 20 of each disc, a spacer for said discs, means securing the respective discs, sheets of colored material and sheets of abradant material to the opposite ends of said spacer, a weighty member rotatable about said spacer, 25 and pyrophoric members projecting from opposite sides of said weighty member and adapted to engage said abradant sheets respectively.
6. The combination of two spaced discs, with window openings therein, sheets of colored material covering said openings, two sheets of abradant material, one on the inside 30 of each disc, a spacer for said discs, two U-shaped members, one on the outside of each of said discs, string sections attached respectively to the ears of said U shaped members, means securing the respective U shaped members, discs, sheets of colored material and sheets of abradant material to the opposite 35 ends of said spacer, a weighty member rotatable about said spacer, and pyrophoric members projecting from opposite sides of said weighty member and adapted to engage said abradant sheets respectively.
- 40 7. A toy having a whirling member, means for whirling the same first in one direction and then in the other direction, said whirling member comprising two spaced discs rigidly connected, a weighty member journaled between said discs and free to rotate with respect thereto, abradant material carried by one of said members, pyrophoric means carried by the other of said members and engaging said abradant material to produce sparks 45 which are visible when looking at the device radially between said discs.
8. Spark producing mechanism comprising spaced rotatable members, an inertia member between said rotatable members, one 50 of said members comprising an abradant sur-
- face, a pyrophoric member carried by another of said members, and means for producing relative movement between said rotatable members and said inertia member.
9. Spark producing mechanism comprising spaced members, a transverse rod connecting said members, an inertia member disposed on said rod between said spaced members, one of said members comprising an abradant surface, a pyrophoric member carried by another of said members, and means for rotating said spaced members to produce movement thereof with respect to said inertia member.
- 70 10. Spark producing mechanism comprising spaced disks, a transverse rod connecting said disks, said disks comprising abradant surfaces disposed in facing relation, an inertia member loosely disposed on said rod between said disks, pyrophoric material carried by said inertia member for engagement with said abradant surfaces, and means for rotating said disks to produce movement thereof with respect to said inertia member.
- 75 11. Spark producing mechanism comprising spaced disks, a transverse rod connecting said disks, said disks comprising abradant surfaces disposed in facing relation, an inertia disk loosely disposed on said rod between said spaced disks, pyrophoric material carried by said inertia disk for engagement with said abradant surfaces, and means for rotating said spaced disks to produce movement thereof with respect to said inertia disk, said spaced disks outwardly of said inertia disk being unconnected to each other.
- 80 12. In testimony whereof I have signed my name to this specification.
